G. Quaale

UNITED STATES PATENT OFFICE.

GILBERT QUAALE, OF WELDON, SASKATCHEWAN, CANADA.

WASHBOILER RACK.

Application filed April 28, 1925. Serial No. 26,461.

The invention relates to improvements in wash boiler racks and an object of the invention is to provide an open rack constructed to receive clothes and other articles to be washed and designed to enter the customary wash boiler and provided with handles whereby the same can be readily placed in and removed from the boiler.

A further object of the invention is to construct the handles so that they can be utilized for supporting the clothes containing rack in an elevated position within the boiler thereby permitting the ready draining of the clothes before they are removed from the boiler.

With the above more important objects in view, the invention consists essentially in the arrangement and construction of parts hereinafter more particularly described, reference being had to the accompanying drawing, in which:—

Fig. 1 is a perspective view of the rack.

Fig. 2 is a side view of the rack as it appears in the boiler, the boiler being shown in vertical section.

Fig. 3 is a view similar to Figure 2 with the rack in draining position.

Fig. 4 is an end view of the rack.

Fig. 5 is a perspective view of one of the suspending hooks or catches.

In the drawing like characters of reference indicate corresponding parts in the several figures.

The rack 1 is of a shape such that it will just nicely fit within the customary wash boiler 2. As is well known, wash boilers are usually made with semi-circular ends and flat sides and the rack which I provide has semicircular ends 3 and 4 and straight sides 5 and 6 connecting the ends.

In the present instance, the rack is formed from upper and lower wire frames 7 and 8 and an intermediately positioned reinforcing wire 9. Suitably spaced stay or vertical wires 10 connect the wires 7, 8 and 9 and horizontal intersecting cross and lengthwise extending wires 11 and 12 form the bottom of the rack, these latter wires having their ends connected to the lower frame 8. The side and bottom forming wires can be continuous if so desired.

Obviously the open rack so formed can

be readily filled with clothes or other material to be washed and then placed in the boiler and the boiling water is free to circulate through the clothes to effect the washing.

Handles 13 and 14 are provided for lifting or lowering the rack and these handles are also utilized to suspend the rack in an elevated or draining position within the boiler. It will be noticed that each handle is formed from wire bent to provide a loop which is pivotally attached to the ends of the frame wire 8. The handles take a position within the ends of the rack and they are provided with outstanding hooks or catches 15 and 16 which overhang the reinforcing wire 9. When the handles are not in use, these hooks or catches prevent the handles from falling inwardly.

When one wishes to wash the clothes in the boiler, the rack is placed in the boiler, the handles being drawn in so that the hooks will not catch on the top of the boiler. The clothes are then put in the rack and boiled in the usual way. When the boiling has been completed, the handles are grasped and the rack with the clothes therein is raised until the hooks are above the upper edge of the boiler. One then draws the handles outwardly towards the ends of the rack to catch the hooks on the ends of the boiler as shown in Figure 3. The hooks then act to suspend the clothes so that they can drain. After draining, the rack can be removed from the boiler.

The wires of the rack are spaced apart a distance sufficient to prevent the smaller pieces of clothes from escaping from the rack and the frame forming wires are sufficiently heavy to give rigidity to the structure. If desired, the handles can be provided with grips of any approved type.

What I claim as my invention is:—

A drain rack comprising a basket formed of wire and including a reinforcing frame member extending entirely around the body of the basket above the bottom wall thereof, a pair of vertically disposed handle members located within and at opposite ends of the basket and having their lower extremities pivoted to the bottom wall of the basket and outwardly directed hook members car-

ried by said handle members including horizontal portions passing above said reinforcing frame member and terminating in downward projections engageable with members affording means for suspending the rack from the upper edge of a boiler or other receptacle in which the rack is used.

- 5 the outer side of said reinforcing frame member to limit inward swinging movement of the handle members, said hook

Signed at Birch Hills, Saskatchewan this 24th day of March, 1925.

GILBERT QUAALE.
